GEORG SEIBT, OF BERLIN-SCHONEBERG, GERMANY.

TELEPHONE TRANSMISSION.

Application filed February 9, 1921, Serial No. 443,695, and in Germany January 23, 1920.

(GRANTED UNDER THE PROVISIONS OF THE ACT OF MARCH 3, 1921, 41 STAT. L., 1313.)

This invention relates in general to improvements in telephone transmission and more particularly to a method of improving transmission in central battery telephone systems in which receivers whose efficiency is enhanced in comparison with the average known type of receiver are employed.

It has often been proposed to increase the loudness of receivers by making the pole pieces of alloyed iron, by using laminated iron instead of solid iron or by other means which tend to increase the permeation of the pole pieces, as for example the adoption of a magnetic by-pass at the point where the pole pieces are joined to the permanent magnet (see German Patent 301,311).

But the advantages derived from these measures were not sufficiently marked to give rise to the general adoption of the improved type of telephone receiver.

The object of the present invention is to turn to account a specific property of the improved type of receiver which is that at a given inductance of the receiver the energy consuming resistance of its coils is considerably lower than in the case of the ordinary receivers in vogue. The expression "energy consuming resistance" as used herein means the total losses in the system or circuit or any part thereof. In other words, this resistance is not equal to but greater than the resistance for continuous current. For the purposes of illustration a few numerical values will be adduced.

35 A standard receiver with pole pieces of flat solid iron with three slots to reduce eddy currents, and with coils whose resistance to continuous current is $W_g=60$ ohms, has a self-induction of $L=0.035$ henries.

40 With alternating current of a frequency of 900 alternations the energy-consuming resistance is $W_w=133$ ohms.

An improved receiver with pole pieces of iron laminæ of a thickness of 0.8 mms. and 45 a magnetic by-pass, and a self-induction of $L=0.04$ henries has a resistance to direct current of $W_g=27$ ohms and an energy-consuming resistance to alternating current amounting to $W_w=59$ ohms.

50 This shows that with the same current strength an improved receiver will not only produce a louder sound, but will also consume less energy than an ordinary standard

receiver. Such improved receivers may be termed low loss receivers. In the above example the ratio of the energies consumed in the two receivers is as 133 I^2 is to 59 I^2 , where I denotes the current strength.

In the central battery telephone system the receivers are connected to induction coils or transformers as shown in the drawing in which Fig. 1 is a diagrammatic representation of the circuits when two lines are connected for conversation.

Fig. 2 is a longitudinal section and

Fig. 3 is an end view of a transformer or an induction coil used for carrying the invention into effect.

B is the central battery at the exchange, D a choke coil, $a-c$, $b-d$, $a-e$, $b-f$ the two subscribers' lines, M_1 and M_2 the transmitters, and T_1 , T_2 are the transformers from which energy is taken by the receivers at the substations.

In large towns the resistance of a line of average length connecting a subscriber to his exchange is about 300 ohms. This is also the approximate value of the transmitter resistance. A standard induction coil or transformer of the type now generally employed in connection with a receiver represents an apparatus with a self-induction of about 0.047 henries and an energy-consuming resistance to alternating current of 120 ohms. These values are obtained while the receiver is connected to the transformer by connecting the terminals of the primary coil by a bridge and making a measurement of self induction and resistance.

When the receiver is disconnected, i. e. when the secondary coil of the transformer T carries no load, the self-induction L of its primary coil S_1 is 0.11 henries, its resistance W_g to continuous current 16 ohms and the energy-consuming alternating current resistance $W_w=30$ ohms.

The secondary coil S_2 itself when disconnected from the receiver has a self-induction of $L=0.064$ henries at a continuous current resistance of $W_g=26$ and an alternating current resistance of $W_w=35$ ohms.

Now if an improved receiver, whose electrical data is given above, is connected to the same transformer the values measured at the terminals of the primary coil will be

$L=0.045$ henries and an energy-consuming resistance $W_w=60$ ohms, or in other words the same transformer that, when connected to the old type of receiver, represented an energy-consuming resistance in the line of 120 ohms only represents 60 ohms when the new receiver is connected to it.

This resistance of 60 ohms is small in comparison with the resistance of the other parts of the line circuit. Hence the former resistance could be considerably increased without noticeably affecting the strength of the talking current.

Now the specific object of the invention is to alter the properties of the transformer in such a manner that it will cause a stronger current to be supplied to a receiver of the improved type.

This can be accomplished by increasing the self-induction of the primary coil S_1 . This will be demonstrated by the following short calculation:

Let L_1 be the self-induction of the primary coil S_1 , L_2 the self induction of the secondary coil S_2 , M the coefficient of mutual induction of the two coils and L_T the self-induction of the receiver.

The E. M. F. produced in the coil S_2 is ωMI_1 , I_1 being the current strength in the line or primary coil S_1 .

In calculating the current I_2 in the secondary coil S_2 or in the receiver the ohmic resistances i. e., the pure ohmic resistance for continuous currents, and the other energy-consuming resistances (losses due to eddy currents and hysteresis) may be disregarded as negligible. All resistances except those due to inductance are disregarded in the formula. Hence the current in the receiver is

$$I_2 = \frac{\omega MI_1}{\omega(L_2 + L_T)}$$

The coefficient M in transformers in which the magnetic dispersion is small—as in the case of ordinary transformers—is practically equal to

$$\sqrt{L_1 L_2}$$

so that we may put:

$$I_2 = I_1 \frac{\sqrt{L_1 L_2}}{L_2 + L_T}$$

It follows that I_2 increases linearly with L_1 . Hence if a transformer with a primary coil of greater self-induction is inserted in the talking circuit the current I_2 will actually be increased. At the same time an increase of the energy-consuming resistance in the line represented by the combination of the transformer and the receiver is obtained. This increase of the energy consuming resistance in the line is due to the increased self induction of the coils. The

secondary coil has a back working effect to the primary coil which is effective in the line as increased resistance when the induction of the primary coil is increased.

The object aimed at thus appears to be attainable in a most simple manner. But a very undesirable secondary effect is also obtained and this is that the inductance which the transformer inserts in the line when supplying current to the receiver grows very appreciably.

It was pointed out above that the primary coil of a transformer or induction coil of the type now in vogue represents, when supplying current from its secondary coil to the receiver, a self-induction of 0.047 henries. At a cyclic frequency of $\omega=5000$ this represents an alternating current resistance of 240 ohms. This impedance is connected in series with a transmitter resistance of about 300 ohms and an average line resistance also amounting to about 300 ohms. Hence this impedance does not greatly affect the strength of the current in the line, particularly as it is only to be added as a vectorial magnitude. But the state of things will be entirely changed if the self-induction of the primary coil S_1 is increased more and more without any counter-acting measures being adopted. The impedance of the transformer when supplying current from its secondary coil may then considerably exceed the ohmic resistance of the transmitter and the subscriber's line which would result in a considerable weakening of the talking current.

The prevention of this undesirable effect is a matter of primary importance. The method of accomplishing this in accordance with the invention consists in simultaneously increasing the self-induction of the secondary coil S_2 of the transformer.

The result obtained by doing this will become apparent from the following calculation:

Let E be the voltage at the terminals of the primary coil S_1 ; call the self-induction of this coil L_1 , let the self-induction of the secondary coil S_2 be L_2 , the coefficient of mutual induction M , and let L_T be the self-induction of the receiver. Then, if the energy-consuming resistances be left out of account and symbolical expressions be adopted, the following equations will be applicable:

$$E = i\omega L_1 I_1 + i\omega M I_2$$

$$0 = i\omega(L_2 + L_T) I_2 + i\omega M I_1$$

Hence since

$$M = \sqrt{L_1 L_2}$$

$$E = i\omega L_1 \left(1 - \frac{L_2}{L_2 + L_T}\right) I_1$$

It follows that a transformer supplying

current to a receiver will represent an impedance in the line with a self-induction of

$$L_1 \left(1 - \frac{L_2}{2L + L_T} \right)$$

5 From this formula it will be evident that this inductance may be decreased in any desired measure by increasing L_2 . If L_2 is very large in comparison with L_T , i. e. if 10 the self-induction of the receiver as compared with the self-induction of the secondary coil of the transformer may be left out of account, the impedance in the line would approximate zero.

15 The ideas underlying the invention may be briefly recapitulated as follows:

Receivers with an improved magnetic circuit do not only produce louder sounds but also have a smaller energy-consuming resistance. 20 If a receiver of this kind is connected to the ordinary type of induction coil or transformer of a subscriber's instrument the energy-consuming resistance of the transformer supplying current to the receiver 25 will still be small. This resistance could be increased without appreciably weakening the talking current. By suitably proportioning the windings of the transformer stronger currents are obtained in the receiver without increasing the resistance in 30 the line to such an extent as to be detrimental. Increasing the self induction of both coils increases the resistance in the line, but not to such an extent as to be detrimental, 35 that is, without appreciably weakening the talking current. The changes made in the transformer consist in increasing the self-induction of its two coils. An increase of the self-induction of the primary coil 40 alone would be sufficient if it were not for the fact that the impedance of the transformer would become too great and thus weaken the talking currents. To obviate this the self-induction of the secondary coil 45 is also increased.

Values that may be adopted for the self-induction of practical induction coils or transformers are $L_1=0.24$ henries for the primary coil and $L_2=0.1$ henries for the secondary coil. 50 These values, however, may be varied. The values, for instance, may be increased to twice or three times those mentioned, but as such values are increased more wire is required without increasing the out- 55 put sufficiently to warrant the additional cost. The values may also be less than those stated; for instance, $L_1=0.18$ and $L_2=0.08$. In this case, while the effect is good, it is not as good as for the values first mentioned. 60 These values of self induction, characterizing my improved transformer, are taken when the transformer is not under load, that is, when the receiver is disconnected, and when the term "self induction" is used 65 in the claims it is to be understood to mean

a self induction whose value is determined when the receiver is disconnected, or when not under load.

When an improved receiver with a self-induction of $L_T=0.04$, a resistance to continuous current of $Wg=27$ and an energy consuming resistance of $Ww=59$ is connected to a transformer of this kind the values measured at the terminals of the transformer are: $L=0.05$ and $Ww=100$. 70 The values $L=0.05$ and $Ww=100$ are measured at the terminals of the primary transformer coil while the receiver is connected to the secondary coil.

By practical tests it will be found that 80 the loudness of the sound emitted by an improved receiver that is first connected to an ordinary or standard induction coil and then to a transformer of the novel type 85 will be increased in the latter case by about 30%.

In order to obtain the greater self-induction required of the novel type of transformer the present form with its open magnetic circuit is preferably departed from 90 and a design of the kind shown in Figs. 2 and 3 adopted.

As shown in Fig. 2 the magnetic circuit of this transformer is completely closed. It consists of thin iron punchings about 0.15 95 of a millimetre in thickness. On account of the small magnetic reluctance the quantity of copper needed in the windings is smaller than that required in the ordinary type of induction coil, even though its self induction is greater. The measurements indicated in Figs. 2 and 3 are in millimetres and if these are adopted and the primary coil is made of 1400 turns and the secondary coil of 940 turns, the values of the self-induction will be those hereinbefore stated, 100 viz. $L=0.24$ and $L_2=0.1$ henries. The thickness of the wire is 0.21 millimetres.

It may be mentioned here that the magnitude of the self-induction of the receiver 110 may be selected arbitrarily. To obtain the effect that it is the object of the invention to accomplish the self-induction of the transformer must be adapted to that of the receiver in such a way that the quotient of the 115 two self-inductions exceeds

$$\frac{0.064}{0.04}$$

In the example described above this quotient 120 was

$$\frac{0.1}{0.04}$$

If the self-induction of the receiver were 125 made twice as great, i. e. 0.08, the self-induction of the secondary coil of the transformer would also have to be doubled.

I claim:

1. The herein described method of effi- 130

- ciently utilizing low loss receivers in a telephone system having such a receiver and a transformer, which consists in increasing the impedance of both coils of the transformer so as to transfer to said receiver through said transformer increased amounts of sound producing energy while maintaining the strength of the current in the line practically unchanged.
- 19 2. The herein described method of efficiently utilizing low loss receivers in a telephone system having such a receiver and a transformer, which consists in increasing the self-induction of the primary coil of said transformer so as to supply proportionately increased amounts of energy through said transformer to said receiver without appreciably decreasing the strength of the current in the line.
- 20 3. The herein described method of efficiently utilizing low loss receivers in a telephone system having such a receiver and a transformer, which consists in making the self-induction of the primary coil of the transformer of a value greater than 0.11 henries so as to supply increased amounts of sound producing energy to said receiver through said transformer, and in giving such values of self-induction to the secondary coil of the transformer and to the receiver that the quotient of their respective self-inductions is greater than $\frac{0.064}{0.084}$, so as to maintain the strength of the current in the line practically unchanged.
- 35 4. The herein described method of efficiently utilizing low loss receivers in a telephone system having such a receiver and a transformer, which consists in increasing the

value of self-induction of the primary coil so as to transfer increased amounts of energy 40 to the receiver through the transformer and in so fixing the values of self-induction of the coils of the transformer and receiver as to maintain the strength of the current in the line practically unchanged. 45

5. The combination in a telephone system of a telephone receiver having a given self-induction, and a transformer for transferring energy to said receiver and comprising a primary coil having a self-induction 50 greater than 0.11 henries whereby more energy is transferred than through a primary coil of .11 henries, and a secondary coil having a self-induction greater than 0.064 henries and at least 1.6 times greater than the 55 self-induction of said receiver, whereby the strength of the current in the line is nevertheless maintained unchanged.

6. The combination in a telephone system of a telephone receiver having a given self-induction and a minimum resistance, and a transformer for transferring energy to said receiver and comprising a primary coil having a self-induction of approximately 0.24 henries whereby more energy is transferred 60 than through a primary coil of .11 henries, and a secondary coil having a self-induction greater than 0.064 henries and approximately 2.5 times greater than the self-induction 65 of said receiver, whereby the strength of the current in the line is nevertheless maintained unchanged. 70

In testimony whereof I have signed this specification.

GEORG SEIBT.
